UNITED STATES PATENT OFFICE.

EMORY GLENN SIMPSON, OF DETROIT, MICHIGAN, ASSIGNOR TO FISHER BODY CORPORATION, OF DETROIT, MICHIGAN, A CORPORATION OF NEW YORK.

ROTARY BROACHING-MACHINE.

1,376,734.

Specification of Letters Patent.

Patented May 3, 1921.

Application filed January 2, 1920. Serial No. 348,966.

To all whom it may concern:

Be it known that I, EMORY GLENN SIMPSON, a citizen of the United States, residing at Detroit, in the county of Wayne and State of Michigan, have invented certain new and useful Improvements in Rotary Broaching-Machines, of which the following is a specification.

This invention relates to a rotary broaching machine and has for its object a broaching machine which can be used to simultaneously plane off the side edges of a metal member such as the leaves of a hinge, and other members of like character that need finishing. The blade carriers are in continuous rotation and consequently the work is very much expedited.

Apparatus for picking up and carrying the work into the path of the rotating broach blades is provided. This is set into operation by the foot of the operator and suitable devices are provided in the machine for picking the work up only at the required time to get into the path of the blades. The various features and improvements will be best understood when the machine is understood in detail.

In the drawings—

Figure 1 is a plan view of the machine, the horizontal section shown being taken through the rotating blade carriers.

Fig. 2 is a side elevation taken from the right side of Fig. 1.

Fig. 3 is a rear elevation of the machine.

Fig. 4 is an elevation of the face of the blade carrier.

Fig. 5 is a section on the line 5—5 of Fig. 4.

Fig. 6 is a section on the line 6—6 of Fig. 4.

Fig. 7 is a front elevation of the blade carriers indicating the progressive depth of cut of the blades.

Fig. 8 is a vertical section through the machine bed showing in side elevation the work carrier in two positions of its travel.

Fig. 9 is a vertical section and enlarged detail of the work carrier.

Fig. 10 is a perspective of the work-supporting block.

Fig. 11 is a detail of one of the blade-holding blocks.

Fig. 12 is a section on the line 12—12 of Fig. 8.

Fig. 13 is a cross-section of the clutch longitudinally of the shaft.

Fig. 14 is a side elevation of the machine mounted upon its support.

Fig. 15 is a section taken substantially on the line 15—15 of Fig. 1 showing the brake 60 for the work carrier drive.

Fig. 16 is a section on the line 16—16 of Fig. 1 showing the clutch release.

Fig. 17 is a perspective of the clutch release cam.

Fig. 18 is a section through the clutch longitudinally of the shaft showing the clutch release cam releasing the clutch plunger.

Referring to Fig. 14, possibly the most comprehensive view of the machine is 70 shown. *a* designates a standard or pedestal on which the rotary broaching machine is mounted. The broaching machine frame is a casting *b* which needs no detailed description nor illustration as any suitable casting 75

to hold the moving and rotating parts will serve the purpose. In Fig. 14, *c* designates the combined pulley wheel and fly wheel. Referring to the plan view shown in Fig. 1, it will be seen that the pulley wheel shaft is 80 journaled in suitable pillow blocks with caps *d* and extends through to the opposite side of the machine where a pinion *e* meshes with a large gear *f* and serves as a gear reduction. This large gear *f* is journaled in 85 suitable journal bearings provided with caps *g*. It will be seen that blade carriers *h* are clamped to this shaft by the clamps *i*.

Now referring to Fig. 4, a face elevation of the blade carrier will be seen and it will be 90 noticed that the clamp *i* is merely a split hub that fits over the shaft *j*, to which the hub is keyed at *k*. Figs. 4 to 7 inclusive contained on this sheet will give an adequate idea of what the blade carrier is like. The 95 blades are designated *l* and are held in tapered recesses *m* by means of the tapered blocks *n* that can be secured to the blade carrier by the screws *o* which engage through elongated slots in the blocks. The 100 bosses *p* are located at the ends of the blade recesses and through them are threaded the screws *q* which are adapted to wedge the blocks *n* in the recesses. Referring to Fig.

7, it will be seen that the blades are projected progressively farther from front to rear to cut progressively deeper into the work. The two blade carriers *h* do not carry the blades directly but an insert *r* is secured to the blade carriers by the screws *s* 110 and this insert carries the blades.

The blade carriers or segments are rotat-

ing continuously. The work is carried to the blades by the work carrier detailed in Figs. 8, 9 and 12. The slide *t* runs in a dove-tailed track *u* (Fig. 12) formed by bolting the strips *v* to the bosses upon the sides of the machine bed *b*, and also slides on a rib *w* in the middle of the dove-tailed groove. This slide *t* is somewhat triangular in general conformation (see Figs. 8 and 9) and on its forward face it is recessed as at *x* to receive the work-holding block *y*. On the forward end is bolted a clamping plate *z* provided with a pair of spring-pressed plungers 1. The work plate and the clamping plate are here shown of suitable configuration and arrangement to accommodate the leaf of an automobile door hinge. This is simply slipped in between the work block and the clamping plate and the two plungers 1 afford sufficient friction to hold the work in place. It may not, however, be accurately centered. Provision is made for centering the work by providing the blade carriers with hard steel inserts. The one on the left hand blade holder is designated 2 (Figs. 4 and 7) and is beveled off at its forward end as shown in Fig. 7. The one on the right tool holder is designated 3 and is also of hardened steel but is yieldable, being projected outwardly by a stiff coil spring 300. Hence the first thing that happens when the two blade-carrying segments strike the work is these two beveled plates strike and move the work on the work block to a properly centered position with respect to the two sets of broach blades which are shown in Fig. 7 as being of increasingly greater projection to cut deeper into the work.

As already explained, the broach-carrying segments rotate continuously and are contained under a proper hood (not shown) to protect the workman. It becomes necessary to bring the work within the range of the broach-carrying segments. This is accomplished automatically when the pedal 4 shown in Fig. 14 is depressed. This is connected with a rod 5, which as shown in Fig. 16, connects with a clutch-releasing cam 17. This withdraws the clutch-releasing cam 17 from engagement with the pin 18 on the clutch plunger 19. This clutch plunger is shown in Fig. 18. In this figure the pin 18 rests in the groove 20 in the side of the cam (see Fig. 17). As soon as this cam is withdrawn the head of the clutch plunger may bear against the side of the clutch-driving disk 21 (Fig. 18) which is keyed to the shaft *j*. When the plunger socket 22 comes around into registry with the clutch plunger this clutch plunger 19 is driven forward by the coil spring 23 and springs into the plunger socket and thereby locks the clutch-driving disk 21 to the clutch-driven disk 24. Referring to Fig. 2, it will be seen that this

clutch-driven disk 24 is nothing more or less than a crank with a connecting rod 25 secured thereto which connects with the work slide *t* already described.

The operation is simple: Supposing the work slide be in the position shown in the dotted lines of Fig. 8—the workman simply inserts the hinge leaf in between the work-holding block and the clamping block, the friction pins 1 serving to hold it from dropping out; he depresses his foot against the pedal 4 and releases the clutch cam 17 which in turn releases the clutch plunger; the head of this plunger then wipes the face of the clutch-driving disk, which is continuously rotated. When the plunger socket 22 comes into registry with the plunger 19 the plunger immediately jumps into the socket and locks the two disks together. They then rotate together causing the connecting rod 25 to pull the work slide *t* into the path of the rotating segments. These rotating blade-carrying segments strike the slide at the time it has come to rest by reason of striking the stop 50 which holds the slide while the connecting rod is permitted to continue due to the yielding coupling furnished by the slot 51, plunger 52, and plug 53 (Fig. 8). The connecting rod does not again pick up the slide until the broach blades have passed through the work.

Inasmuch as the work block *y* is not on a true radius and the blades are, they deliver a shearing cut to the hinge leaf. Also note that the work block is on an inclination that causes the blades to strike first the upper or outside portion of the work and hence the stress of the blades tends to drive the work against the block and hold it in the clamp.

As soon as the workman releases his foot on the pedal the clutch-releasing cam 17 springs back against the periphery of the driven-clutch disk 24, as shown in Fig. 16. The forward end 26 is beveled, as shown clearly in Fig. 17. Hence when the pin 18 of the clutch plunger 19 strikes this beveled face it is caused to withdraw the clutch plunger 19 from its socket 22 and the clutch-releasing pin 18 then rests in the recess 20 of the releasing cam until this cam is again withdrawn by the depression of the foot upon the pedal 4. When the pin 18 again rests in the recess 20, the work slide again remains at rest in open position for the workman to take out the hinge leaf and insert another, whereupon the same operation, depressing the pedal 4, etc., takes place. The brake shoe 30 (Fig. 15) is constantly pressed against the driven-clutch disk 24 and causes enough drag to prevent the momentum to carry the work-carrier beyond its proper position when the clutch parts are disconnected.

The hub clamps of the blade carriers may be loosened and the carriers adjusted along

the shaft by the spacing screw 55 and the clamping bolt and nut 56 (Fig. 1).

What I claim is:

1. A rotary broaching machine, having in combination, a rotating blade carrier, broaching blades projecting therefrom in the direction of the axis of rotation, and means for supporting the work in the path of the rotating blades and holding the same stationary during the operation of the blades thereon, said means operable to bring the work forward into the path of the blades and backward out of the path of the blades. 10
2. A rotary broaching machine, having in combination, a rotating blade carrier, broaching blades carried therein and progressively increasing in projection in the direction of the axis of rotation and from the forward blade to the rear to increase the depth of the cut, and means for supporting work in the path of said blades. 15
3. A rotary broaching machine, having in combination a rotary blade carrier, broaching blades radially supported therein, and means for supporting the work in the path of the blades but at an inclination to a radial line so that the radially-disposed blades strike first the outside of the work and travel in upon the work. 20
4. A rotary broaching machine, having in combination, a rotary blade carrier, broaching blades carried therein, and a work slide for sliding the work in and out of the path of the rotating broaching blades. 25
5. A rotary broaching machine, having in combination, a rotary blade carrier, broaching blades carried therein, a slide slidable in and out of the path of the broaching blades, and means for automatically sliding the work in and out of the path of the broaching blades when the said automatic means is actuated. 30
6. A rotary broaching machine, having in combination, a rotary blade carrier, means for rotating the same, a slide adapted to carry the work in and out of the path of the blades, and connections between the rotating means and the slide for carrying the slide in and out of the path of the work when said connections are set to operate. 35
7. A rotary broaching machine, having in combination, a rotary blade carrier, broaching blades supported therein, means for rotating the carrier, a work slide sliding in and out of the path of the blades, reciprocating connections for the slide between the rotary means and the slide and including a clutch whose parts engage to cause the said connections to reciprocate the slide to bring the work in and out of the path of the blades. 40
8. A rotary broaching machine, having in combination, a rotary blade carrier, blades carried therein, a slide for supporting the work and sliding the same in and out of the path of the blades, means for rotating the 45
- blade carrier, and connections between the rotary means and the work slide including a clutch which can be actuated to cause the connections to pick up the slide and pull the work into the path of the blades and back it out of the path of the blades and which is provided with means for automatically releasing the connections with the slide when the slide has been backed out. 50
9. A rotary broaching machine, having in combination, a rotary blade carrier, broaching blades therein, means for rotating the carrier, a slide for sliding the work in and out of the path of the blades, and connections between the rotating means and the work slide including a clutch and a clutch-releasing cam, the clutch being provided with a clutch plunger, and a pair of clutch disks, said cam normally holding the plunger from locking the two disks together and when the cam is released the one disk being adapted to pick up the plunger to rotate the two disks together for a complete revolution whereupon the cam disengages the clutch plunger and stops the slide after it has been backed out. 55
10. A rotary broaching machine, having in combination, a continuously rotating blade carrier, broaching blades carried therein, a work slide adapted to slide in and out of the path of the blades, means for rotating the carrier, and connections between the carrier and the slide for reciprocating the slide and including a clutch made up of two disks, a clutch plunger, a clutch plunger pin, a releasing cam provided with a pin recess and a beveled forward end, the said releasing cam when released allowing the plunger to wipe the other disk and be picked up by the other disk to lock the two disks together and the said beveled end of the cam serving to disengage the plunger when the disks have made a complete rotation together so as to stop the work slide when it has been backed out of the path of the blades. 60
11. A rotary broaching machine, having in combination, a pair of rotating blade carriers spaced apart from each other, broaching blades secured therein and having progressively greater projection toward the opposite carrier from the first blade to the last blade, and means for rotating the carriers, the said blades adapted to straddle the work and simultaneously broach two sides of the same. 65
12. A rotary broaching machine, having in combination, a pair of blade carriers spaced apart, means for rotating the same, broaching blades carried in each carrier, and work-centralizing devices secured on the carriers in advance of the broaching blades to centralize the work before it is struck by the broaching blades. 70
13. A rotary broaching machine, having in combination, a pair of rotary broach car- 75

riers, broaching blades carried in each carrier, means for rotating the carrier, and work-centralizing devices carried on the carrier in advance of the blades and comprising one a beveled surface and the other a beveled yieldable surface.

14. A rotary broaching machine, comprising a pair of spaced apart rotary blade carriers, broaching blades carried therein and projecting in the direction of the axis of rotation, means for rotating the blade carriers, means for supporting the work stationary in the path of the blades while they are operating on the same, and means for ejecting the work after the blades have passed over the same.

15. A rotary broaching machine, having in combination, a segment acting as a blade carrier, blades carried on the segment, means for continuously rotating the segment and means for ejecting the work from the path of the blades when they have passed by.

16. A rotary broaching machine, having in combination, a segment acting as a blade carrier, broaching blades secured in the segment, means for supporting the work, and means for picking up the work support and sliding it into the path of the blades at a predetermined time before the blade segment comes into the position where the cutting is done.

17. A rotary broaching machine, having in combination, a segment for carrying the blades, broaching blades carried on the segment, means for rotating the segment continuously, means for supporting the work, means for picking up the work support and sliding it into the path of the blades at a predetermined time before the blades come into the position where the cutting is done, and means for ejecting the work support out of the path of the blades after the blades have passed by the work.

18. A rotary broaching machine, having in combination, a blade segment, broaching blades carried therein, and a work support in the form of a clamp and work-supporting block, the same being inclined with respect to the broaching blades so that the blades jam the work into the clamp and block in passing over the same.

19. A rotary broaching machine, comprising a rotary blade carrier, means for rotating the same, broaching blades carried on the carrier, a slide for supporting the work, and means for reciprocating the slide to bring the work into the path of the blades before the blades come into the cutting position and for taking the work out of the path of the blades after the blades leave the cutting position.

20. A rotary broaching machine, having

in combination, a rotary blade carrier, broaching blades carried in the carrier, means for rotating the carrier continuously, a slide for supporting the work, and means for reciprocating the slide to bring the work into the path of the blades before the blades reach the cutting position and to take the work out of the path of the blades after the blades have passed the cutting position, said means including devices for keeping the work slide stationary during the cutting operation.

21. A rotary broaching machine, having in combination, a rotary blade carrier, broaching blades carried therein, means for rotating the carrier, a slide for supporting the work, and means for reciprocating the slide to bring the work into the path of the blades before the blades reach the cutting position and to take the work out of the path of the blades after the blades leave the cutting position, the said means including a connecting rod that has a yieldable connection with the slide and a stop that stops the slide before the connecting rod reaches the limit of its movement, which stopping of the slide permits the same to remain stationary during the cutting operation.

22. In a broaching machine, the combination of a rotary carrier, broaching blades carried thereon, means for rotating the carrier, and a work support comprising a slide, a block and a clamp, the latter two having an inclination with respect to the inclination of the blades to cause the blades to tend to jam the work into the clamp when they are engaged in the cutting operation.

23. In a rotary broaching machine, the combination of a rotating carrier, means for rotating the same, broaching blades projecting therefrom a progressively greater distance from the first one to the last one in the direction of the axis of rotation, and a work support, the said elements being arranged to bring the blades intermittently into cutting relation with the work which is stationarily held during the cutting operation.

24. In a rotary broaching machine, the combination of a rotating blade carrier, broaching blades projecting from the carrier in the direction of the axis of rotation, means for rotating the carrier, and means for supporting the work stationarily with respect to the blades when the same are operating on the work, said elements being arranged so that the blades are brought only intermittently into contact with the work so as to allow replacement of the work.

In testimony whereof I affix my signature.

EMORY GLENN SIMPSON.
